O. S. TEALE,
RETOUCHING MACHINE,
APPLICATION FILED JAN. 30, 1919.

1,386,910.

Patented Aug. 9, 1921.

Inventor
Oscar S. Teale,

by Joel B. Liberman Attorney

UNITED STATES PATENT OFFICE.

OSCAR S. TEALE, OF BLOOMFIELD, NEW JERSEY, ASSIGNOR TO GEORGE H. WILEY,
OF NEW YORK, N. Y.

RETOUCHING-MACHINE.

1,386,910.

Specification of Letters Patent. Patented Aug. 9, 1921.

Application filed January 30, 1919. Serial No. 274,131.

To all whom it may concern:

Be it known that I, OSCAR S. TEALE, a citizen of the United States of America, and a resident of the city of Bloomfield, 5 county of Essex, State of New Jersey, have invented and do hereby lay claim to certain new and useful Improvements in Retouching-Machines, of which the following is a description and specification.

10 My invention relates to improvements in instruments used by photo-engravers and others for the purpose of retouching photographic negatives when it is desired to produce a tone simulating the texture, particularly of flesh or fabric. This result is accomplished by a combination of mechanical and electric or other contrivances coöordinated to, and specifically arranged for the purpose intended.

20 The accompanying drawings will now be referred to to more fully describe the invention, of which:

Figure 1 is a longitudinal section of an instrument embodying the novel features of 25 this invention.

Fig. 2 shows a portion of the instrument viewed at right angles to Fig. 1.

Figs. 3, 4 and 5 are transverse sectional views on line 3—3, 4—4 and 5—5, Fig. 1 30 respectively.

The cap 6, is secured to the main or central portion 7 of the casing by being screwed on the bearing 8 of the drive shaft, which bearing is by its screw thread securely held 35 stationary in a counter screw thread in the top of the central portion 7. The casing is completed by a section in the form of a perforated plug or bushing 9, which is screwed into a recess formed in the lower end of 40 the central portion 7, and butts against the end of the bearing 10, of the pencil carrying shaft, said bearing having a flange 11 formed to seat in the recess in the end of the central portion 7, and is thereby held in 45 fixed axial position.

The drive shaft is composed of two parts 12, and 13, which are held in axial alignment by the end of part 12 fitting in a socket 14, formed on the upper end of part 50 13, said socket being formed with a slot into which fits a feather or spline 15 on the part 12 whereby while the two parts of the shaft may be longitudinally adjusted they will under all circumstances be relatively the axis of the shafts 13 and 28, when

the bearing 20 is longitudinally shifted by the finger pieces 25. A firm and positive joint between the ends of the shafts 13 and 28 is provided by this hinge connection, insuring positiveness of action of the ends 60 of the shaft 28, revolving around the axis of the instrument in varying circles, the diameters of which are determined by the angular settings of the link 36.

I claim:

1. In a retouching instrument, a drive shaft, a pencil carrying shaft and a universal bearing therefor in line co-axial with the drive shaft in combination with an adjustable connection positively joined to the adjacent ends of the two shafts and means for setting the connection, whereby the end of the pencil carrying shaft may be set in different radial positions relatively to the axis of the drive shaft and revolved around said 75 axis in unison with the rotation of the drive shaft.

2. In a retouching instrument, a drive shaft, a pencil carrying shaft and a universal bearing therefor in line co-axial with the drive shaft in combination with an adjustable connection comprising a link and pivots on which its ends are free to rock and by which it is positively joined to the adjacent ends of the two shafts and means 80 for setting the connection, whereby the end of the pencil carrying shaft may be set in different radial positions relatively to the axis of the drive shaft and revolved around said axis in unison with the rotation of the 85 drive shaft.

3. In a retouching instrument, a drive shaft, a pencil carrying shaft and a universal bearing therefor in line co-axial with the drive shaft, said shafts having slots 95 formed in their adjacent ends, in combination with a flat link with its ends fitted to work in the slots and pivotal pins or bolts passing through the sides of the slots and the flat link, and means for varying the distance between the universal bearing of the pencil carrying shaft and the link connected end of the drive shaft.

4. A retouching instrument, comprising a drive shaft, bearings therefor, a pencil or 105 stylus carrying shaft provided with a universal bearing mediate its ends and longitudinally stationary in line coaxial with the bearings of the drive shaft, a casing in which the bearings are held, a link pivotally con- 110

5 nected at its ends to the adjacent ends of the two shafts and means for varying the distance between the ends of said shafts longitudinally the axis and coincidently setting and holding the ends of the pencil carrying shafts away from the axis.

5. A retouching instrument, comprising a drive shaft, bearings therefor, a pencil or stylus carrying shaft provided with a universal bearing mediate its ends having a flange at one end and longitudinally stationary in line coaxial with the bearings of the drive shaft, a casing in which the bearings are held consisting of a main central portion having a screw threaded recess at

its lower end into which the flange of the universal bearing is seated, a bushing screwed into the recess against said flange and a cap piece secured to the upper end of the central portion, a link pivotally connected at its ends to the adjacent ends of the two shafts and means for varying the distance between the ends of said shafts longitudinally the axis and coincidently setting and holding the ends of the pencil carrying shafts away from the axis. 20 25

OSCAR S. TEALE.

Witnesses:

MAYER BRITWITZ,
JOHN J. TRESIDDER.
